UNITED STATES PATENT OFFICE

FALCONER O'BRIEN, OF DETROIT, MICHIGAN, ASSIGNOR TO L. A. YOUNG SPRING & WIRE CORPORATION, OF DETROIT, MICHIGAN

SPRING STRUCTURE

Application filed September 19, 1929. Serial No. 393,638.

The main object of this invention is to provide in a spring structure an improved bracing means for supporting against lateral movement.

5 A further object is to provide a bracing means for cushion and like spring structures which is effective in supporting the parts braced and does not materially detract from the resiliency of the body springs.

10 Objects pertaining to details and economies of my invention will definitely appear from the description to follow. The invention is defined in the claims.

A structure embodying the features of my 15 invention is clearly illustrated in the accompanying drawing in which:

Fig. 1 is a fragmentary plan view of a spring cushion structure embodying the features of my invention.

20 Fig. 2 is an enlarged fragmentary view in section on line 2—2 of Fig. 1.

Fig. 3 is an enlarged fragmentary plan view showing details of the bracing means.

In the embodiment illustrated the body 25 springs 1 are of the hour-glass type. The top coils of these springs are connected to a top border frame 2 by means of clips 3. The bottom border frame 4 illustrated is of the **S** type, that is, of **S** cross section, having an inwardly facing channel clamped upon the bottom coils of the outer springs and an outwardly facing channel adapted to receive the upholstery. The springs are connected by clips 5.

35 The braces 6 are provided with laterally turned ends 7 secured to the top border frame by means of the clips 8. The brace supporting members 9 are of channel cross section and mounted upon intermediate coils of a pair 40 of adjacent springs by clamping such coils of the springs within the channel. The channel is also clamped upon a helically coiled coupling member 10 with which the laterally turned pintle-like portion 11 of the brace is 45 engaged. This coupling member is engaged upon the brace before it is clamped within the channel. The coupling member may be engaged with the portion 11 by rotating the coupling member or threading it over the part 11.

50 The brace is thus very securely connected

to the member 9 and at the same time it is supported for free pivotal movement without strain on the parts and without noises.

I have illustrated two of these braces, but it will be understood that as many may be used 55 as desired. I have not attempted to illustrate other embodiments or adaptations of my improvements as it is believed this disclosure will enable those skilled in the art to embody or adapt the same as may be desired. 60

Having thus described my invention what I claim as new and desire to secure by Letters Patent is:

1. The combination in a spring structure 65 of a plurality of coiled body springs, a top border frame, a member of channel cross section clamped upon intermediate coils of a plurality of body springs, a coiled coupling member clamped within the channel of said member, and a brace secured at one end to 70 said border frame and having a laterally disposed pintle-like coupling engaging portion disposed within the coils of said coupling member.

2. The combination in a spring structure 75 of a base element a plurality of body springs connected thereto, a top border frame, a brace supporting member of channel cross section operatively connected to said base element, a coiled coupling member clamped within the 80 channel of said support member, and a brace secured at one end to said border frame and having a laterally disposed pintle-like coupling engaging portion disposed within the coils of said coupling member. 85

3. A spring structure comprising an assembled set of coiled springs, an element to be braced, a brace connected to said element, a channel-shaped brace supporting element clamped upon the coils of adjacent springs, 90 and a coiled coupling member disposed within the channel of said supporting element, said brace having a laterally disposed portion disposed axially within the coils of said coupling member. 95

4. A spring structure comprising an assembled set of springs assembled with a base element, an element to be braced, a brace connected to said element, a channel-shaped brace supporting element operatively connected 100

nected to said base element, and a coiled coupling member disposed within the channel of said supporting element, said brace having a portion engaged within the coils of said coupling member.

5 In witness whereof I have hereunto set my hand.

FALCONER O'BRIEN.
